Inventor.
T. H. CASHMAN,
By Matthew Murphy
A.D. 1875.

UNITED STATES PATENT OFFICE.

THOMAS WILLIAM CASHMAN, OF LONDON, ENGLAND.

FURNACE.

Application filed November 8, 1923. Serial No. 673,617.

To all whom it may concern:

Be it known that I, THOMAS WILLIAM CASHMAN, a subject of the King of England, and resident of 163^a Strand, city of London, in the Kingdom of England, have invented certain new and useful Improvements in Furnaces, of which the following is a specification.

My invention relates to furnaces and more particularly to improved means of the kind adopted for effecting smoke consumption and fuel economy, in such a manner that one furnace will consume the smoke of another furnace, there being at least two furnaces of ordinary construction working conjointly.

The necessity and advantages as well as the general practice hitherto adopted for smoke consumption are too well known to need any particular reference in this specification.

I am aware that a ventilator was used in connection with a mixing chamber which mixed the whole of the combination gases with heated fresh air and which is then forced by the fan back through the water and steam space, thence into the furnace box and through perforated pipes beneath the grate.

My invention differs from known apparatus in that I draw the gases from the flues by a powerful fan, to increase the velocity of the gases and create the necessary circulation essential for the proper working, i. e. to create forced draught in one boiler to get rid of the flue gases from other boilers so giving a better chemical combination, increasing the temperature of the fire, and reducing the amount of CO and unburnt carbon which is absolutely essential for complete combustion and fuel economy.

In addition I carry conduits externally of and separate from the furnace proper and can thereby adopt my construction to existing furnaces with a minimum of alteration.

According to this invention the conduits lead from the rear of the flues to a common shaft through which they are strongly drawn by a powerful fan and then forced along an upper external flue at the forward end of which are distributing branches to conduct the gases back to a series of perforated inlet tubes fitted below the fire bars or hearth.

In order that my invention may be clearly understood and readily carried into effect I will now proceed to describe the same

fully with reference to the accompanying diagrammatic drawings, in which:—

Figure 1 is a side elevation of a boiler installation fitted with my improved apparatus; Fig. 2 is a plan; Fig. 3 is an end elevation; and Fig. 4 is a section on line AB of Fig. 1.

Although three boilers are shown in these drawings, the invention is applicable to a two boiler installation or to any number of boilers.

According to this invention smoke is drawn by a fan 1 from the rear of the furnace flues 2 through short vertical pipes 3 and transverse rear conduit 3^b into a common shaft 3^a and then forced through piping or passages 4 and along an upper longitudinal shaft 4^a, at the forward end of which are branch pipes 4^b which conduct the gases back through down pipes 4^{b*} to an inlet or 75 inlets 5 leading to outlets beneath the fire where they issue directly beneath the fire bars or hearth and are consumed at once by the flames.

To improve this effect, the smoke and 80 gases are caused to enter the furnace through a series of short tubes 6 closed at their ends, projecting from the main return conduit 5 beneath the fire, these tubes 6 being perforated or slotted suitably over their length. 85

The fan may be driven by a motor 7 or otherwise.

In operation, the flues of the boilers whose smoke is to be consumed are shut off from the chimney by closing the dampers 11 usually provided for the purpose of controlling the draught. Simultaneously dampers 8 provided in pipes 3 are opened, so that the whole of the combustion products of these boilers are passed through the apparatus to 95 the boiler which is intended to consume said products. This latter is the only boiler of the battery whose main flues remain open to the chimney 9 and closed to the apparatus, and in which dampers 10 in the inlet pipes 100 5 are also open. Thus the whole products of combustion of the remaining boilers are passed through the fire of one boiler, which may be any desired one of the battery, i. e. that one which has the brightest fire. By 105 this arrangement rubbish and coal of inferior quality can be burnt in all the boiler furnaces except one which has a more or less non-bituminous fire, into which the combustion products enter and are consumed. A 110

great economy in fuel cost is thus effected without the usual smoke nuisance, while the whole apparatus is external of the furnaces, boilers or other usual fixtures and may 5 therefore be fitted to an existing plant in the space of a few hours and without interfering with the operation of same, the only structural alteration required being the removal of a brick from the rear flue of 10 each furnace for the connection of pipes 3 thereto.

It will be seen that with this simplified construction very little cost is entailed and no dismantling, cutting and drilling of the 15 boiler shell is necessary in application to existing boilers and no additional furnace is required. The invention is applicable to marine or locomotive types of boiler.

I claim:

20 Means for effecting smoke consumption in a battery of furnaces whereby the whole

smoke of any of the furnaces can be passed through the fire of any other of the furnaces, comprising in combination with furnace flues which lead directly to the chimney and 25 are provided with dampers, a transverse conduit, short vertical pipes connecting the flue of each furnace to said transverse conduit, a common shaft longitudinally disposed above said furnaces and connected to said transverse conduit, a transverse branch pipe connected to said shaft, down pipes leading from said branch pipe to beneath the grates 30 of the furnaces, means for controlling the entrances of said vertical pipes and the exits 35 of said down pipes, and means for forcing flue gases through the pipe system, the whole system of pipes, conduits and shaft being external of the furnaces and the boilers associated therewith, substantially as described.

THOMAS WILLIAM CASHMAN.
